UNITED STATES PATENT OFFICE

RUDOLF LOEB, OF VENTNOR, NEW JERSEY

EDGE FOLDING AND SECURING MEANS FOR SEWING MACHINES

Application filed December 15, 1926. Serial No. 154,904.

My invention relates to edge folding and securing mechanism employed with sewing machines in the preparation of fabric material for various purposes, and the main object of my invention is to provide means for preparing an edging strip or ruffle material of two sections of fabric, one of which is narrower than the other.

A further object of my invention is to arrange guiding and folding mechanism whereby independent sections or strips of fabric material which may be of different character and/or color may be prepared and presented to a needle whereby they may be sewn together in the formation of an edging or ruffle strip to be subsequently applied to the material to be ornamented, or simultaneously applied thereto, and wherein one of said independent strips or sections of material, which may be the narrower one, occupies such position with respect to the other independent strip of material that the turned or folded edge of said narrow strip projects beyond the turned or folded edge of the other strip; producing an effect of "piping" when such strips are secured together in overlaid position.

In one instance the folding or guiding mechanism employed to prepare this duplex strip of material operates upon one edge of each piece of fabric whereby such edge is turned or folded over and said folded edges with their inturned portions adjacent each other are presented to a needle to be sewn together, with one edge projecting beyond the other; such mechanism producing a complete article which may be subsequently employed as the ruffled edge of a curtain structure.

In another instance, the folding or guiding mechanism for operating upon the independent sections making up the duplex strip of material is so arranged with respect to stitching mechanism, that both edges of the two strips of material employed may be turned or folded and applied directly at a single operation to the broad face of a section of fabric which may be a curtain structure; such turned edges with their folded or inturned portions adjacent each other and with one

of said edges projecting beyond the other being simultaneously sewn together and to the body of the curtain by zigzag stitching whereby the underlying and contrasting color edge, which projects beyond the edge of the overlying piece or strip, will give the effect of a "piped" edge.

In the operation of a third arrangement of the folding and/or guiding mechanism, the effect of a piped edge is produced by forming the narrow strip of material substantially into the form of a cord. For such purpose, one of the folding and/or guiding devices, that employed for the narrower strip of material, is constructed so as to curl the same into a substantial solid cord, which occupies the position of the so-called "piping", and is secured to the body of the material to be ornamented together with the wider strip of material, preferably by zigzag stitches.

These and other features of my invention are more fully described hereinafter, reference being had to the accompanying drawings in which:

Figure 1 is a perspective view of the presser-foot and needle of a sewing machine; such presser-foot being shown as provided with superposed folding guides.

Fig. 2 is an end view of the folding guides shown in Fig. 1, looking in the direction of the arrow.

Fig. 3 is a view of the same character as Fig. 1, illustrating another form of guiding means which may be employed in the formation of an ornamental two-part seam edging.

Fig. 4 is an end view showing another form of folding guide structure which may be employed in the formation of a two-part seam edging.

Fig. 5 is a view illustrating another form of guide for one of the strips, within the scope of my invention.

Fig. 6 is a face view of two sections or strips of material in the connected condition produced by the guiding and sewing means shown in Fig. 1; one section or strip having an edge projecting beyond the other to represent "piping".

Fig. 7 is a sectional view of the structure shown in Fig. 6.

Fig. 8 is a sectional view of the seam edging produced by the means shown in Fig. 3.

Fig. 9 is an edge or sectional view of the seam or edging produced by the guiding means shown in Fig. 4, when associated with stitching means, and

Figs. 10, 11 and 12 are views of portions of curtain structures, showing the application thereto of the edge trimming or ornamentation consisting of the duplex sections of material; one part or portion of which duplex section produces the piped edge.

In the drawings, 1 represents the presser-foot of a sewing mechanism, carrying folding guides 2 and 3; the guide 2 being disposed adjacent the bed plate of the sewing machine and adapted to receive and effect the turning or folding of the edge of a relatively broad piece or strip of fabric indicated at A, and the guide 3 surmounting the guide 2, and receiving and serving to turn or fold the edge of a narrow strip of fabric, indicated at B. By preference, a guiding element 4 is mounted in advance of the guide 2; said guiding element 4 serving to impart a temporary bend or fold to the fabric A. These strips A and B pass to the guiding means from supply rolls, and may be under more or less tension.

30 The folding guides 2 and 3, are provided with inturned lips 5 and 6, respectively, around which the edges of the fabric are turned or folded for passage beneath the presser-foot where they are caught and held together by a row of through stitches x, applied by the needle 7, from the thread 8.

The guides carried by the presser-foot 1 are so disposed with respect to each other that the upper guide 3 projects laterally a slight distance beyond the lower guide 2, so that the laterally turned edges of the two pieces of fabric A and B, such turned edges being indicated at a and b, are presented to the needle 7, with the turned or folded edge b projecting a slight distance beyond the turned or folded edge a, as shown in Fig. 1. By such arrangement of the guides the finished strip, (illustrated in Figs. 6 and 7, and which may be utilized as trimming material 50 for curtains and the like), has the edge b of the narrower strip of fabric disposed beyond the edge a of the broader strip of fabric; imparting what may be termed a "piped" edge effect to the material so prepared. This 55 piped edge strip may be subsequently applied to curtain fabric or material such as indicated at C, and illustrated in Fig. 10, and sewn to the latter.

By the use of guiding means for the independent strips of material which are delivered to the presser-foot and subsequently sewn together, such as illustrated in Figs. 1 and 2, the effect is to fold over the edge of each strip of material and to bring these 65 folded edges into juxtaposed position, with

the folded edge b of the narrower strip superposed upon the folded edge a of the broader strip, and projecting a slight distance beyond the same. When viewed from the front, as indicated in Fig. 6, for instance, the folded edge of the narrower strip will present or produce what may be termed a "piped" edge effect with respect to the folded edge of the broader strip. This duplex strip of fabric, illustrated in Figs. 1 and 6, is completed by the sewing operation indicated, and may then be applied as a ruffled edge to a piece of curtain fabric, for instance, illustrated at C, in Fig. 10.

In some instances, however, it may be desirable to sew the two strips, A and B, to the material to be ornamented at a single operation and in Fig. 3, I have illustrated a view of another form of presser-foot 1^a, carrying guides 2^a and 3^a, which presser-foot is recessed at 9, on the under side, to accommodate the narrower strip of fabric B, which is folded by the guiding means and turned twice, as indicated at b', so that it forms a thicker edge or body. This edge is sewn down by zigzag stitches x', applied by a needle 7^a, and, as clearly illustrated in Fig. 8, these stitches pass through the turned or folded edge a' of the strip A.

In another arrangement, the guide or folding device may be constructed to turn or curl the narrow strips as to produce, substantially, a cord, and in Fig. 4, I have shown a rear elevation of guiding means which may be employed for this purpose; guides 2^b and 3^b, being superposed upon each other; the latter guide serving to fold the narrow strip of material B. These two guides present the two strips of material A and B to the point of sewing in such relation that the narrower strip is given a double infold substantially as indicated at b², in Fig. 9, while the folded edge a of the broader strip will be brought against the same and the two held down by a row of zigzag stitches x², (applied by a needle in the manner indicated in Fig. 3); such stitches being more particularly illustrated in Figs. 9 and 12. Another form of guide which may be employed to effect the inturning of both edges of the narrow strip of fabric B, is shown at 3^c in Fig. 5, and might be employed in lieu of the guide 3^b.

Fig. 10 illustrates diagrammatically a portion of a curtain structure C to which the duplex strip of material shown in Fig. 6, and formed by the guiding and/or folding means illustrated in Fig. 1, has been applied as a ruffled edge; two rows of stitching indicated at y serving to hold the same in place. Fig. 11 shows the effect of simultaneously applying the strips A and B to a piece of fabric C' by mechanism such as illustrated in Fig. 3, a line of zigzag stitches x' overlying the projecting and doubled portion b of the strip B and also securing the turned edge a of the

strip A. Fig. 12 shows the application of the strip B which has been delivered in corded form by folding means such as illustrated in Figs. 4 and 5; such corded edge being held by overlaid zigzag stitches α^2 which also engage the folded edge α of strip A. No claim is made to the fabric structure or seam shown herein, the same forming the subject of my Patent No. 1,627,543, dated May 3,

1929.

10 I claim:

In edge folding means for sewing machines, the combination of a presser-foot, a pair of edge folding devices disposed in line with and operatively connected to said presser-foot; said folding devices being fixedly arranged in such cooperative relation that independent strips of material presented thereto for single edge folding may be delivered in superposed position with the folded edge of one strip projecting beyond the folded edge of the other strip, and a folding guide for one of said strips disposed in advance of the presser-foot and independently thereof.

20 25 In witness whereof I have signed this specification.

RUDOLF LOEB.
